UNITED STATES PATENT OFFICE.

JACOB MARK, OF NEW YORK, N. Y.

DESIGN FOR A TILE.

SPECIFICATION forming part of Design No. 31,209, dated July 11, 1899.

Application filed February 24, 1899. Serial No. 706,737. Term of patent 14 years.

To all whom it may concern:

Be it known that I, JACOB MARK, of the borough of Manhattan, in the city of New York, in the county of New York, and in the State of New York, have invented and produced a certain new and original Design for a Tile; and I do hereby declare that the following is a full, clear, and exact description thereof.

Figure 1 is a perspective view of a tile embodying my design, and Fig. 2 is a plan view thereof.

Letters of like name and kind refer to like parts in each of the figures.

The object of my invention is to provide an original and ornamental configuration for tiles; and to this end said invention consists in the design for a tile substantially as herein set forth.

The leading feature of my design consists

of a quadrangular or four-sided figure, each 20 of whose sides is a plane surface interrupted by V-shaped or angular notches.

In the annexed drawings, A designates a tile having four plane sides, in each of which sides are several angular or V-shaped notches 25 B and B.

Having thus described my invention, what I claim is—

The design for a tile, substantially as herein shown and described. 30

In testimony that I claim the foregoing I have hereunto set my hand this 23d day of February, A. D. 1899.

JACOB MARK.

Witnesses:

JACOB L. MARK,

HENRY W. ABBOTT.
